ORNAMENTAL KNOB AND THE FORMATION
THEREOF

David E. Johnson, Rockford, Ill.

Application November 11, 1932, Serial No. 642,201

3 Claims. (Cl. 29—161)

This invention relates to ornamental knobs for use on furniture, woodwork, and the like, and has more particular reference to the formation of a knob having a flange at the base of the knob heads adapted to abut against a wood or other surface when the knob is tightened into place.

One object of the invention is to provide as a new article of manufacture a screw or knob of the above character forged from a single piece of wire and having an integral annular collar or flange forming an abutment shoulder at the juncture of a threaded shank and a head having a base portion of larger diameter than said shank.

Another object of the present invention is to provide a novel process of manufacture by which a knob of the above character may be formed from a single piece of wire of uniform cross-section.

In carrying out the foregoing object, the process involves shaping a piece of wire to form an annular shoulder between opposite end portions of different diameters and forming an outwardly projecting flange from the metal of the larger end portion adjacent said shoulder.

The invention also resides in the novel method of forming the head flange from the metal of the shouldered blank.

Other objects and advantages of the invention will become apparent from the following detailed description taken in conjunction with the accompanying drawing, in which

Figure 1 illustrates the different steps involved in the formation of a knob according to the present invention.

Figs. 2 and 3 are fragmentary sectional views of the dies and work pieces showing their relation at different times in the formation of the knob flange.

Fig. 4 is an enlarged section view showing a knob made in accordance with the present invention turned or screw-threaded into a piece of wood.

Figs. 5, 6 and 7 are views similar to Figs. 2, 3 and 4 illustrating the manner of manufacture and use of a knob having a different type of shank.

Referring first to the Figs. 1 to 4, the knob illustrated therein comprises a head 8 having an end of any desired ornamental shape and a base 9 which preferably tapers rather sharply adjacent the head and then more gradually to a substantially uniform diameter near its end which merges along a curved surface 10 into an annular flange 11. The latter preferably has a curved outer peripheral edge 12 and its diameter is proportioned relative to the head to give the desired artistic appearance. The surface 13 of flange 11 opposite the head is usually disposed at right

angles to the axis of the knob and thus is adapted to abut against the face of the wood piece 14 to which the knob is applied by screwing a threaded shank 15 into the wood.

The process contemplated by the present invention involves the use of work-blanks 16 formed by cutting successive predetermined lengths from a wire of stock of the proper uniform diameter. The blanks are then operated upon in a heading machine of well known construction, one end of

the blank being upset in one or more operations and then forged into the desired shape with the base 9 thereof preferably tapering to a substantially uniform diameter at its end. In the heading operation or in a different forging operation, a shoulder 17 is formed intermediate the ends of the blank with its outer peripheral edge merging with the base 9 and its inner edge merging into a shank 18 of uniform diameter and somewhat shorter in length than the screw-

threaded shank 15 eventually to be formed. In order to give the desired curvature to the outer edge of the flange 11, as will later appear, the surface of shoulder 17 preferably is beveled and tapers toward the shank 18.

In the present instance, the flange 11 is formed by shearing back the metal of the base 9 beginning at the shoulder 17 while the base or head is unsupported laterally. To position the shouldered blank accurately for this operation, the blank is supported through the medium of its shank 18 which is suitable for this purpose. The blank is then projected into one end of a bore 19 of a diameter slightly greater than the shank and thus adapted to snugly receive the latter. The bore 19 is in a die 20 having a flat face defining a cutting edge at the open end of the bore. With the blank thus firmly supported, it is forced into the bore a predetermined distance beyond the shoulder 17 which may be accomplished by relative axial approaching movement between the die 20 and a plunger or block 21 having a socket 22 shaped to receive the end of the head 8. In this movement, the metal at the end of the base 9 is sheared back as shown in Fig. 3 along the diameter of the shank 18 beginning at the shoulder 17, the cutting edge of the die at the open end of the bore 19 serving to effect the desired shearing action. The metal thus removed from the outer peripheral portion of the base 9 at the end thereof spreads outwardly as the blocks 20 and 21 move toward each other thereby forming the flange 11. Upon separation of the blocks, the work-piece is ejected in the usual way by project-

ing a pin 22^a through the bore 19 into abutment with the end of the shank 18.

The radial width of the flange 11 is determined by the extent to which the base 9 is forced into the die. It has been found that a flange of substantially radial width may be formed without danger of cracks being formed at the outer peripheral edge of the flange 11. The shearing operation, it will be observed, occurs without any external lateral support for the head 8 and its base 9. Notwithstanding this, the base 9 is not disfigured and the flange is formed with the graceful curve 10 adjacent the end of the base 9. The curve 12 which is desirable from the standpoint of artistic appearance is due in part to the beveled character of the shoulder 17.

By avoiding the provision of lateral support for the base 9 during the shearing operation, it will be apparent that this operation is greatly simplified and the cost of the equipment required reduced to a minimum. This is made possible by supporting the shouldered blank through the medium of the shank 18 during the shearing operation. With this method of support during shearing, the blank is held firmly and accurately in centered position relative to the cutting edge of the die insuring the formation of a flange of uniform radial width.

The surface of the flange 11 on the side opposite the head 8 will be shaped according to the contour of the face of the die 20 and the major portion of this surface will ordinarily be disposed in a plane perpendicular to the shank 18. When the knob is to be screwed into wood as shown in Fig. 4, it is preferred to shape the outer surface adjacent the shank in which recess the cuttings 24 formed as the knob is screwed into the wood may accumulate thereby permitting the flange to be drawn tightly and squarely against the face of the board. The recess 23 may, if desired, be formed in the flange-forming operation above described. To this end, a narrow annular ridge 25 is formed on the face of the die 20 at the end of the bore 19.

In the shearing operation, the metal flows around this ridge having the recess 23 in the flange, the outer surface 13 of the flange being perpendicular to the knob axis.

After formation of the flange 11, the shank 18 is threaded by the use of well-known screw-threading machinery. After cutting of the last thread adjacent the flange 11, the threading tool is allowed to dwell adjacent the flange so as to form an annular groove 26 communicating with the under cut recess 23 and affording additional space in which the wood-cuttings may accumulate.

For certain applications, the knob is secured to the board by a screw 27 projecting through the board from the opposite side thereof and threading into the shank 18. In the case of such knobs the shank is not threaded externally but is tapped to form a bore which is later threaded to receive the screw 27. The method of forming the flange on knobs of this latter character is

generally similar to the method first described as will be seen from Figs. 5 and 6, a somewhat shorter but larger shank 18 being formed by varying the size of the bore 19 and the extent of relative movement between the dies 20 and 21. For this type of knob, the die 20 would be formed with a flat face forming a corresponding-shaped perpendicular surface 13 on the flange 11.

With the process above described, it will be apparent that an ornamental knob having a flanged base may be forged from an integral piece of wire of uniform diameter with a minimum number of operations. The process lends itself to high speed production with minimum equipment and labor costs and makes possible the formation of knobs of more rugged character and more artistic appearance than those now in service use.

I claim as my invention:

1. For forming a knob having an ornamental head and a shank at opposite ends with an annular ornamental flange projecting radially from the base of said head, the process which comprises forging a piece of wire to form said head at one end of the wire, a circular shoulder at the base of and facing away from said head and an end portion of uniform cross-section, projecting the end portion into a die recess snugly receiving the same, and forcing the wire into the die without lateral support for the base of the head whereby to lengthen said shank and shear back the metal at the base of said head so that the natural flow of the metal forms an annular flange at the juncture of said shank and the base of said head.

2. For forming a one-piece screw knob having an enlarged head and a threaded shank at opposite ends with an annular flange providing a radially disposed abutment shoulder at the base of said head, the process which comprises forging one end of a piece of wire to form an enlarged head with a base extending therefrom and terminating at an annular shoulder of smaller diameter, the other end portion of the wire forming a shank of uniform diameter less than said base and merging with said shoulder, projecting said end portion into a continuous annular die hole receiving such end and supporting the wire, applying an end thrust to the end of said head to cause the die to shear back the metal of said shank and thereby form said flange, and thereafter threading said shank.

3. As a new article of manufacture, a screw knob formed from a wire blank and comprising an enlarged head forged at one end of the wire, an intermediate portion of smaller diameter than the head, a threaded stem of smaller diameter than the intermediate portion, and an integral radial collar at the junction of the intermediate portion and the stem, said collar adapted to be formed by shearing back the metal of part of the cylindrical portion to produce the collar and providing a shoulder abutment facing said stem.

DAVID E. JOHNSON.
